(57) **CLAIM**

The ornamental design for vehicle body panels, as shown and described.

DESCRIPTION

FIG. 1 is a perspective view of vehicle body panels of the present design showing the vehicle body panels installed on a vehicle;

FIG. 2 is a side view thereof, the opposite side of the vehicle is a mirror image of the side shown; and,

FIG. 3 is a back view thereof.

The broken lines showing of the vehicle in FIGS. 1, 2, and 3 are illustrative purposes only and form no part of the claimed design.

1 Claim, 3 Drawing Sheets

FIG. 1

FIG. 2

FIG. 3
